CHRISTMAS STOCKING

Louis Margolin, New York, N. Y.

Application April 13, 1949, Serial No. 1,957

Term of patent 3½ years

(Cl. D47—7)

To all whom it may concern:

Be it known that I, Louis Margolin, a citizen of the United States, residing at New York city, in the county of Bronx and State of New York, have invented a new, original, and ornamental Design for a Christmas Stocking, of which the following is a specification, reference being had to the accompanying drawing, forming part thereof.

In the drawing:

Fig. 1 is an elevational view of one side of a Christmas stocking showing my new design;

Fig. 2 is an elevational view of the opposite side of the Christmas stocking.

I claim:

The ornamental design for a Christmas stocking, substantially as shown.

LOUIS MARGOLIN.
